MAGNETIC BALL SWITCH FOR ELECTRIC CIRCUITS

Emanuel J. Di Noia, Tarrytown, N.Y., assignor, by mesne assignments, to Aerotec Industries, Inc., Greenwich, Conn., a corporation of Connecticut

Filed July 30, 1959, Ser. No. 830,548

9 Claims. (Cl. 200—87)

My invention relates to a magnetic ball switch for electric circuits.

In the switch of my invention, a pair of spaced contact terminals or pole pieces are mounted in insulating supports within an enclosure and a ball slug is movable into contact with said terminals to close a circuit or out of contact with said terminals to break or open the circuit. The ball slug is of magnetic material and is movable into and out of contact with the contact terminals by means of a movable magnet outside of the enclosure. The magnet is preferably a permanent magnet. The contact terminals or pole pieces and the ball slug are of a material which has no residual magnetism and has a low reluctance and high permeability so that there is no tendency for the ball slug to maintain contact with or stick to the pole pieces after the field of the permanent magnet has moved away.

The permanent magnet is of a material having a high energy product, high coercive force, and good stabilization of wide temperature range. These characteristics allow the magnetic field of the permanent magnet to hold the ball slug firmly against the contact terminals to avoid contact make and break under shock and vibration conditions. These properties of the ball slug, terminals and permanent magnets give the switch a "snap action" since the field build-up and break-down is very rapid. The contact surface area can be varied by varying the shapes or configuration of these elements.

The contact terminals and the ball slug may be enclosed in a tubular enclosure of non-magnetic material and thus protected from corrosive liquids and gases and from adhesion to their surfaces of contact of substances that might impair the electric conductivity through these surfaces. In use, in combustible materials or mixtures, any sparking at the contacts is isolated by the enclosure from the combustible material and danger of explosion is obviated. No sparking would be caused by movement of the permanent magnet in the combustible material.

The various features of my invention are illustrated by way of example in the accompanying drawings in which;

FIG. 1 is a longitudinal section through a double throw switch embodying my invention,

FIG. 2 is a longitudinal section of a single throw switch operable by a float carried magnet to indicate the level of a liquid medium,

FIG. 3 is a section on the line 3—3 of FIG. 2,

FIG. 4 is a longitudinal section of the ball switch as applied to a reactor rod position indicator,

FIG. 5 is a similar section, taken on line 5—5, on a larger scale, of a portion of the switch,

FIG. 6 and FIG. 7 are, respectively, cross sections of the switch on lines 6—6 and 7—7 of FIG. 5,

FIG. 8 and FIG. 9 are longitudinal sections of modifications of the switch applied to a reactor rod position indicator,

FIG. 10 and FIG. 11 are, respectively, longitudinal sections of portions of the switches of FIGS. 8 and 9, on a larger scale, taken on lines 10—10 and 11—11, respectively of FIGS. 10 and 11,

FIG. 12 is a vertical, fore-shortened, section of the ball switch applied to detecting the level of liquid in a tank, a series of switches being mounted in a tube depending from the top of the tank, and,

2

FIG. 13 is a side view on a smaller scale of the tube, the positions of the level being indicated.

In the embodiment shown in FIG. 1, a pair of contact terminals 10 and 11 are mounted in spaced relation in one end of a tube or thimble 12 of dielectric material or a material non-conductive of electricity. The contacts 10 and 11 are held spaced diametrically of the tube by an insulating spacing element 13 which, with the terminals, closes the end of the tube or spindle. Lead wires 14 and 15 are connected to the terminals 10 and 11, respectively. The opposite end of the tube is similarly closed by a pair of diametrically spaced terminals 16 and 17 and an insulating separator 18. Lead wires 19 and 20 are connected to the terminals 16 and 17, respectively.

A ball slug 21 is slidably mounted in the tube 12 and is movable with the magnetic field of a permanent magnet 22 encircling the tube and movable longitudinally from one end of the tube to the other to bring the ball slug 21 alternatively into contact with the terminals 10 and 11 and 16 and 17.

The inner ends of the terminals 10 and 11 and 16 and 17 are of complementary conical curvature and the opposite ends of the ball slug 21 are rounded as at 23 to make a line contact with the terminals. The shape of the ends of the ball slug and of the terminals may be such as to make a contact of any desired width and thus to obtain a path of corresponding area as the slug bridges one of the other pair of terminals.

In the embodiment shown in FIGS. 2 and 3, a pair of diametrically spaced terminals 24 and 25 are similarly mounted in one end of an element 26 having a cylindrical recess 27 at one end. The terminals 24 and 25 are held spaced by a non conducting spacer 28 which, with the terminals, closes the end of the recess. The assembly of recessed elements, terminals and spacers is enclosed in a protective tube 29 having a pair of longitudinal slits 30 at diametrically opposite parts of the tube. This is, in turn, enclosed in a larger tube 31, leaving a space 32. A magnetizable ball slug 33 is slidably positioned in the recess 27 to be moved by a magnetic field from the bottom of the recess into bridging contact with the spaced terminals. The ends of the terminals 24 and 25 and of the ball slug 33 may be shaped as those of FIG. 1.

The above assembly is enclosed in a tube 34 of sufficient diameter to form a float chamber 35 and is closed at the ends by a cap 36 in which the tubes are supported, but one end being shown in the drawings. The wall of the tube 34 is provided with slots 37 to permit the entry and out-flow of fluid.

Within the float chamber a float 38 is slideable vertically on the tube 31 with the rise and fall of the fluid level being guided on the tube by circumferentially spaced guide rods 39. Mounted on the float 38 is an annular permanent magnet 40 to provide a magnetic field or flux through the space within the magnet and within the tubes 31 and 29 at whatever level the float and magnet may be during its rise and fall.

The assembly may be mounted in a liquid container, the axis of the tubes and the element 26 being vertical and with the liquid free to enter and leave the float space 35. As the level of the liquid rises it lifts the float 38 and magnet 40 and thereby the magnetic field of the magnet and when the magnetic field of the float rises to, or nearly to, the level of the terminals 24 and 25, this closes an electric circuit through the bridged terminals from one lead 41 connected to the terminal 24 to a lead 42 connected to the terminal 25. The closing of the circuit may be used to actuate a signal or a control apparatus. When the liquid level falls, the float 38 will fall and the ball slug 33 will drop to the bottom of the recess, opening the circuit.

While but one pair of terminals and ball slug is shown

in FIGS. 2 and 3, it will be understood that this assembly may be repeated at spaced elevations in a container to indicate the level at corresponding intervals in the height of the container.

The pole pieces and ball slug are Hy Mu 80 material having no residual magnetism and very low reluctance and high permeability. The choice of material here may vary as long as the material has these characteristics. Upon removal of the magnetic field of the permanent magnet, materials of these characteristics immediately lose their magnetism and the ball slug immediately breaks away from the terminals.

The permanent magnet is of Indox, a material having a high energy product, high coercive force and good stabilization within wide temperature ranges. Any other material of these characteristics may be used. The magnet need not be circular as bar magnets, horse shoe magnets, and magnets of other shapes may be used. However, ring magnets of the sintered ceramic type are used.

The contact terminals and ball slug may be plated with gold, silver, tungsten or gallium or other metals to provide any desired contact resistivity and their surfaces may be varied to provide any desired contact area.

The enclosing tubes of dielectric material may be of glass, quartz, lavite epoxy resin, Teflon or Kel-F materials.

In FIGS. 4-7 an arrangement of switches of my invention for indicating the position of a reactor rod is shown. In this arrangement a series of switches is placed in spaced, longitudinal sequence in an enclosing tube in such manner that they bridge and close an electric circuit from a common lead to several leads leading from the successive switches to a suitable indicating device. The switches are closed and opened in successive sequence by the magnetic field of a permanent magnet carried on a reactor rod movable lengthwise of the series of switches. Accordingly when the reactor rod is in any position its magnet closes a corresponding switch. The successive circuits closed in this manner actuate the position indicator through a resistance system or other known actuating device.

Referring to FIG. 5, each of a succession of ball slugs 41 is movable in a channel 42 of its switch housing 43 of non-conductive or dielectric material from the position shown in full lines to that shown in broken lines. In the latter position it bridges a pair of spaced contacts 44 and 45, one contact 44 of each switch being connected to a lead 46 connecting these contacts in series and the other contacts 45 being connected to an individual lead 47. All of these leads pass out of the apparatus to an indicating device.

This indicating device is not, per se, a part of my invention and is therefore not illustrated. It may be any suitable electrically operated device as, for example, one in which the lead 46 is grounded and the individual leads 47 are connected between resistances in series to control an indicator operating current or voltage.

The contacts 44 and 45 are separated by a separator 48 of insulating material, which may be an extension of the housing 43 of an adjacent switch. The housings 43 are enclosed in a tube 49 which is slit at 50 and 51, FIGS. 6 and 7, on diametrically opposite sides to permit projections 52 of the contacts 44 and 45 to extend therethrough for connection to the leads 46 and 47. The lead 46 extends longitudinally of the tube in the slot on one side of the tube and is threaded through beads 53 of glass or other insulating material. A washer 54 of dielectric material is placed between successive housings 43, being centered by a round projection 55 of one housing extending into a hole of the washer and having projecting ears 56 to receive the leads 46 and 47. The leads 47 are insulated by a jacket of insulating material which, for use at elevated temperatures, may be of Teflon.

The tube 49 is enclosed in a thimble 57, closed at its free end by a plug 58 recessed to receive one end of the tube 49. It is spaced axially in the thimble by the plug 58 and at intervals in its length by spacers 59 which may

also serve to hold the leads 46 and 47 in position. The other end of the tube is held in a nut 60 which turns freely on the tube and is threaded in threads 61 in the thimble to enable the position of the tube to be adjusted in its axial position relative to the thimble. The nut 60 may be locked in its adjusted position by means of a lock nut 62. The leads pass through a plate 63 spanning the end of the thimble opposite the plug 58. This end of the thimble may be threaded externally for mounting on a fixed part of the reactor structure. The tube, thimble and spacers 59 are of non magnetic material.

The ball plugs 41 are moved to and from the contacts 44 and 45 by a magnetic field generated by a magnetized ring 64 encircling and slidably longitudinally of the thimble. The ring is carried by rods 65 movable longitudinally of the thimble by a moving part of the reactor apparatus. As the ring moves in one direction or the other its magnetic field moves successive ball slugs to or from the contacts, thus putting into or removing successive resistances.

FIGS. 8 to 11 show an arrangement similar to that of FIGS. 4 to 7 except that resistances for the several switches are incorporated in the tube. Corresponding elements are therefore identified with the same reference characters as in FIGS. 4-7.

In the modification shown in FIGS. 8 and 10, the successive switch housings 43 are separated and spaced by resistor housings 66, each containing a resistor 67. An insulated lead wire 68 extends from each resistor to the next and is also electrically connected to the projection 52 of each contact 45 to connect these contacts in series. As the ball slug 41 of each switch is moved by the magnetic field into contact with the contacts 44 and 45 it closes a circuit between the wires 46 and 68 and short circuits the resistors farther from the fixed end of the thimble, thus decreasing the resistance through the circuit.

In the modification shown in FIGS. 9 and 11 the system is similar to that of FIGS. 8 and 10 except that, instead of the wires 68 extending into the housings 66, they are connected to electrically conductive plates 69, one at each end of the housings 43 and electrically connected to the ends of resistance coils 70 wound on insulating spacers 71 extending from one housing to the next.

The magnetic field may be such that combinations of two successive switches can be closed simultaneously so that a continuous stepping indication is provided. For example, switches 1 and 2 close simultaneously, then 2 and 3, then 3 and 4 and so on.

The arrangement of the switches for use with a float is shown in FIGS. 12 and 13. In this arrangement the switch apparatus is mounted in the top of a tank which, as shown in the drawings, is a horizontal, cylindrical, tank and extends vertically downwardly to nearly the bottom. The tank is provided with a mounting plug 72 threaded in an opening in the top of the tank so that it may be removed. The plug has a central hole 73 provided with a lower threaded part 74 of lesser diameter into which is threaded a plug 75 having a projection 76 to which is secured the upper end of a tube 77 similar to the switch carrying tube described above. By screwing the plug upwardly or downwardly, the position of the tube may be adjusted vertically. The tube is slit on diametrically opposite sides and its lower end is closed.

A number of ball slug housings 78 are mounted in the tube, the lowermost resting on the bottom of the tube and each being provided with a pair of spaced contacts 79 and 80 and with each of the housings, excepting the bottom one, resting on the contacts of the housing just beneath it. These housings are of non magnetic, insulating, material. Each pair of contacts may be held spaced by a tongue 81 of the next higher housing extending into the space between the contacts. The housings are held in closely packed contact by a screw plug 82 threaded in a vertical, threaded, hole 83 in the mounting plug 72 and

pressing downwardly on a pressure plug 84 which bears on the uppermost housing.

Each housing has a chamber 85 in which is a ball slug 86 of magnetic material movable vertically upwardly by an upwardly movable magnetic field to bridge the contacts 79 and 80. The contacts 79 are connected in series to a common lead 87 while each of the contacts 80 is connected to an individual lead 88. These several leads extend to resistances, not shown, outside the tank which control electric energy changes which actuate an indicating means.

The tube 77 is enclosed co-axially in a thimble 89 secured at its upper end to the mounting plug 72 and closed at its lower end by a plug 90 having a central recess 91 in which the lower end of the tube is guided in its vertical adjustment.

The thimble 89 is co-axially enclosed in a cylinder 92 secured at its upper end to the mounting plug 72 and having a bottom wall with a recessed, upwardly extending boss 93 in which the plug 90 is positioned. The wall of the cylinder 92 is provided with a series of vertically spaced groups of openings 94 through which liquid may flow into and out of a space 95 between the thimble and the interior surface of the cylinder.

An annular float 96 in the space 95 and encircling the thimble 89 rises and falls with the rise and fall of the liquid level in the space 95 and carries an annular magnetized ring 97 which creates a magnetic field through the walls of the thimble and tube, which are of non-magnetic material, to move the ball slugs of successively higher level into bridging contact with their contacts as the level of the liquid rises and conversely carries ball slugs of successively lower level into contact as the liquid level falls.

The outer surface of the cylinder carries level indicating marks 98 to which the contacts 79 and 80 are made to match by an adjustment of the tube 77.

Through the above combination, the level in the tank may be indicated accurately by an indicator system mechanism outside the tank. Inasmuch as the contacts are enclosed within the thimble they are separated from the liquid and from any combustible vapors in case the liquid in the tank evolves combustible vapors. The magnetized ring 97 cannot cause any sparking.

Having described my invention, I claim:

1. A switch circuit for indicating the position of a movable mass which comprises a thimble of non-magnetic material having one end closed and the opposite end fitted for attachment to a support, the closed end of said thimble having an axially extending guide surface; a tube mounted co-axially in said thimble and being slidably guided by said guide surface for adjustment longitudinally in said thimble, said tube being of lesser diameter than said thimble to provide an annular space; means at the end opposite said guided surface to support said tube in positions of longitudinal adjustment; a series of electric

switches in, and spaced longitudinally of, said tube, each said switch comprising a housing having a longitudinally extending chamber, a pair of spaced contacts at one end of said chamber, and a magnetic ball slug movable in said chamber to bridge said contacts; an electric circuit having connections to said contacts to close short circuits therethrough; a magnetized ring in said annular space movable longitudinally of said tube and encircling said tube to provide a longitudinally movable magnetic field therein to move said ball slugs to and from said contacts.

2. The switch circuit of claim 1 having a lead connecting one of each pair of contacts in series and separate leads connected to the other contacts of each pair of contacts.

3. The switch circuit of claim 1 having insulating spacers between the contacts of each pair.

4. The switch circuit of claim 1 having a rod movable longitudinally of said tube and attached to said magnetized ring to move said ring longitudinally of said tube.

5. The switch circuit of claim 1 having resistances positioned between said switches, a lead connecting one contact of each switch in series with the others and leads connecting each of the other contacts with the resistances positioned between said switches.

6. The switch circuit of claim 5 in which said resistances are enclosed in insulating housings.

7. The switch circuit of claim 5 in which each resistance comprises a spacer of insulating material and a resistance coil wound on said spacer.

8. The switch circuit of claim 1 having a cylinder enclosing and co-axial with said thimble and forming an annular space about said thimble, said cylinder having openings to admit liquid into said annular space through said openings.

9. The switch circuit of claim 8 having means to adjust said tube longitudinally of said cylinder.
